J. KOKSCHAROFF
MECHANICAL PENCIL

1,913,762

Filed Oct. 23, 1930

Inventor:

Johann Kokscharoff

UNITED STATES PATENT OFFICE

JOHANN KOKSCHAROFF, OF BERLIN, GERMANY, ASSIGNOR TO THE WAHL COMPANY,
OF CHICAGO, ILLINOIS, A CORPORATION OF DELAWARE

MECHANICAL PENCIL

Application filed October 23, 1930, Serial No. 490,776, and in Germany January 16, 1930.

This invention relates to mechanical pencils, and particularly to mechanical pencils of the magazine type wherein a magazine is provided for holding a plurality of lead sticks and means is provided for feeding the lead sticks progressively and successively from magazine to writing position without manual handling of the lead sticks.

One of the objects of the invention is the provision of such construction which will facilitate discharge of the lead sticks singly and successively from the magazine into cooperation with the means for positively advancing them.

Another object is the provision of a construction which will be effective to advance the lead sticks to writing position positively and to project the lead from the writing tip to any desired extent, said construction being of a simple character and being susceptible of embodiment in a very sturdy structure within a very small cross-sectional area.

Another object is the provision of such a construction in which the lead in writing position will be held securely against wobbling or lateral movement with respect to the pencil barrel when the pencil is employed in writing.

Yet another object is the provision of a construction having the characteristics above pointed out and which may be very easily assembled.

Other and further objects will be pointed out or indicated hereinafter, or will be apparent upon an understanding of the invention or its employment in use.

For aid in an explanation of the invention, there are shown in the accompanying drawing forming a part of this specification, and hereinafter described, certain structural forms in which the invention may be embodied. It is to be understood, however, that these particular embodiments are here presented for purpose of exemplification, and hence are not to be construed in any fashion calculated to limit the appended claims short of the true and most comprehensive scope of the invention in the art.

In said drawing,

Fig. 1 is a longitudinal sectional view of

a pencil construction embodying the invention, the cap or magazine cover being shown removed and the lead-propelling traveler being shown in fully retracted position;

Fig. 2 is a longitudinal sectional view of the same construction with the magazine cover in place and the lead-propelling traveler in an advanced position;

Fig. 3 is a part longitudinal sectional view of a modified construction embodying the invention;

Fig. 4 is a longitudinal sectional view of a lead guide tube and lead-propelling traveler of further modified form;

Fig. 5 is a cross-sectional view taken on approximately line V—V of Fig. 1;

Fig. 6 is a cross-sectional view taken on approximately line VI—VI of Fig. 2;

Fig. 7 is a cross-sectional view taken approximately on line VII—VII of Fig. 1; and

Fig. 8 is a perspective view of the lead-propelling traveler shown in Figs. 1 and 2.

An understanding of the invention may be gained most quickly from a detailed consideration of the embodiment here illustrated, and which will now be described.

Referring first to the embodiment illustrated in Figs. 1 and 2, it will be seen that the pencil includes a suitable slender hollow barrel 1 which is tapered at its lower end and has a tapered tip 2 abutting its lower end, which tip affords a bore for the passage of the lead stick and is split so as to resiliently clasp a lead stick of proper size in its bore. Rotatably mounted in the hollow barrel and extending throughout a substantial portion thereof is a sleeve 3 having its upper portion of generally cylindrical form and its lower portion formed with an internal screw thread 8. A lead guide tube 4 is mounted on the tip 2, as by having its lower end screwed into a counterbored and threaded upper portion of the tip, as illustrated. Fixedly mounted on the upper end of the lead guide tube is a disk 10 of such diameter as to extend outwardly from the lead guide tube into association with the encompassing wall of the rotatable sleeve 3. This disk is provided with a central aperture 18 in alignment with the bore of the lead guide tube, and has its

80

85

90

95

100

upper surface dished or sloping toward said aperture. The sleeve 3 is retained against withdrawal from the barrel by an inwardly pressed bead 11 which projects under the disk 10. At its lower end the sleeve 3 abuts a spacer 9 which encompasses the lead guide tube and is limited against upward movement by an outwardly displaced lug 12. This spacer is adapted for non-rotatable cooperation with both the barrel 1 and the tube 4, and is thus adapted to prevent relative rotation of said parts.

The lead guide tube is slotted longitudinally through one side, the slot being indicated by the reference numeral 26, whereby the circular continuity of the tube is interrupted and the tube flattened in effect, as illustrated in Fig. 7. A lead-propelling traveler 5 is mounted on the tube so as to slide longitudinally thereon. This traveler is in the nature of a split sleeve, as seen in Fig. 8, conforming in contour to the flattened contour of the lead guide tube, by virtue of which form it is held against rotation on the tube. This traveler carries a lead-engaging member 6, in the form of a pawl or tongue, which is adapted to travel in the slot 26 of the lead guide tube, and which is elastically pressed to urge its lower end or nose portion to a position within the bore of the lead guide tube, as illustrated in Fig. 2. Below the lower end of this lead-engaging member, the traveler carries a lug 24 adapted to ride in the slot 26 without extending into the bore of the tube. The traveler is also provided with outwardly projecting lugs 25, so formed and arranged as to mesh slidably in the thread 8 of the rotatable sleeve 3.

Accordingly, upon rotation of the sleeve 3, the traveler will be propelled longitudinally on the lead guide tube, downwardly when the sleeve is rotated in one direction, and upwardly when it is rotated in the opposite direction. The lead guide tube, it will be observed, remains stationary with the tip and barrel relative to the sleeve 3 when the latter is rotated, and the disk 10 likewise remains stationary with the lead guide tube.

The upper portion of the sleeve 3, above the disk 10, constitutes the wall of the lead magazine, the disk 10 forming the bottom of said magazine. Accordingly, it will be observed, the wall of the magazine rotates with respect to the bottom of the magazine when the sleeve 3 is rotated to propel the traveler. This magazine is adapted to accommodate a plurality of lead sticks, which rest at their lower ends on the disk 10. Lead sticks of proper size are adapted to pass singly and successively from the magazine through the aperture 18 and into the bore of the lead guide tube.

The slot 26 of the lead guide tube is terminated or closed short of the upper end of said tube, as by a short tube section 7 inserted in

a counterbored portion of the lead guide tube, said short tube section having its bore in alignment with the bore of the lead guide tube. Accordingly, when the traveler is retracted to its upper position, the lead-engaging member 6 will be moved into contact with the lower end portion of the tube 7, and retracted entirely from the bore of the tube, to a position as illustrated in Fig. 1. This leaves the bore clear and unobstructed so as to accommodate free passage of lead sticks longitudinally therein. Lead sticks which pass from the magazine through the aperture 18 are thus permitted to feed by gravity downwardly in the lead guide tube. When the tube 3 is rotated to propel the traveler toward the tip, the lower end of the lead-engaging member 6 will ride off of the tube section 7 and drop into the bore of the lead guide tube, where it will engage against the upper end of a lead stick therein, and, upon further movement of the traveler toward the tip, will push the lead stick through the tip bore. The lead may be thus propelled from time to time as required for writing.

In order to induce or facilitate the passage of the lead sticks from the magazine through the aperture 18, there is provided in the magazine a vane or lead-positioning member 17 which extends inwardly into the magazine from the magazine wall. Upon rotation of the sleeve 3, this lead-positioning member engages adjacent lead sticks and tends to propel them around on the magazine bottom and toward the axial aperture 18. This has the effect of inducing the lead sticks to enter the aperture 18, and is of particular advantage in that respect when the pencil is operated in a sloping position.

The magazine cover or cap 19 has a sleeve portion 20 adapted to fit the upper end of the sleeve 3 which projects beyond the upper end of the barrel, and is provided with an inwardly projecting lug 21 adapted, when the cover is placed in position, to pass through a groove 22 and engage in a seat 23, pressed inwardly in the wall of the sleeve 3, thereby keying the cap to the sleeve so that the latter may be rotated by suitable manipulation of the cap. This keying engagement is illustrated in Figs. 2 and 6.

In operation of the device, the magazine being loaded with a plurality of lead sticks and the device being grasped by the barrel and held with the point downward, rotation of the cap in a counterclockwise direction will rotate the sleeve 3, and move the traveler upwardly on the lead guide tube. With such rotation of the sleeve 3, the lead positioning member 17 will engage lead sticks and move them around on the magazine bottom, and displace them toward the aperture 18, facilitating their passage successively through that aperture and into the lead guide tube, down which they will slide by gravity until the

lowermost lead stick is stopped at the restricted bore of the tip. The direction of rotation of the cap being then reversed, the traveler will be moved downwardly on the lead 5 guide tube, the nose of the pawl 6 will slide off of the lower end of the tube section 7 and drop through slot 26 and, with continuation of rotation of the sleeve 3, will engage against the upper end of a lead stick in the 10 tube bore and propel that lead stick and any ahead of it downwardly. The lead may thus be fed so as to be projected from the writing tip as desired from time to time. When the lower end of the traveler contacts 15 the spacer 9, the end of the advancing movement of the traveler will be reached. Thereupon the rotation of the cap and sleeve 3 in the reverse direction will move the traveler upwardly to the position illustrated in Fig. 1, 20 thus permitting the feed of additional lead sticks from the magazine into the lead guide tube, whereupon the pencil is again ready for operation to advance the lead to writing position. In the lead propelling operation, the 25 lug 24 of the traveler slides in the slot 26 of the lead guide tube ahead of the lead-engaging member 6, in which relationship it is adapted to function as a stop to prevent the upper end of the lead stick from being wedged 30 outwardly into the slot by the propelling pressure of the lead-engaging member. This lug 24 is also adapted to function as a stop to limit the upward movement of the traveler when said lug comes into engagement with 35 the end of the tube section 7.

In Fig. 3 is illustrated a modified construction, the barrel being designated 1, the rotatable sleeve 3, and the lead guide tube being designated 4'. In this construction the 40 lead guide tube is provided with a plurality of longitudinal slots at different circumferential locations, said slots being designated 26' and 26'', and the traveler 5' is provided with a plurality of tongues 6' and 6'', which 45 operate through respective slots in the manner above described. In Fig. 3 the lead-engaging members are shown at positions 180° apart, while in Fig. 4 they are shown at a 90° relationship. In such a construction having 50 a plurality of lead-engaging members at different positions longitudinally of the traveler, a lead stick may be fed to the full length of travel of the traveler when the upper end 55 of the lead stick is engaged by the upper lead-engaging member, and then may be further advanced after a lower lead-engaging member has been brought into engagement with its upper end by a sufficient retraction 60 of the traveler. The reverse movement of the traveler in this instance need not be the full length of a lead stick, the actual distance requisite for such reverse movement of the traveler being dependent, of course, on the 65 distance which the successive lead-engaging

members are spaced apart longitudinally of the traveler.

In assembling the device, the traveler is slipped onto the lead guide tube and the latter inserted into the sleeve 3 at the upper end, 70 the spacer 9 is slipped onto the lead guide tube at the lower end, and the parts thus assembled are inserted into the barrel at its upper end. The tip 2 is then inserted into the lower end of the barrel and screwed onto the lower 75 end of the lead guide tube. This secures the parts in assembled relationship.

The drawings being merely illustrative, it will be appreciated that in some places space 80 is shown between portions which are actually in contact, this being done in order that the various thin parts may be more clearly shown.

I claim:—

1. A magazine pencil comprising, in combination, a hollow barrel portion, a lead guide 85 tube mounted non-rotatably therein, a sleeve mounted rotatably in the barrel in encompassing relationship to the lead guide tube and having its upper end extending above the upper end of the lead guide tube to form a magazine wall, a disk mounted on the upper end of the lead guide tube to form the magazine bottom extending into association with said magazine wall, said disk having a central aperture therethrough in alignment with 90 the bore of the lead guide tube, means operable by rotation of the sleeve relative to the lead guide tube to propel a lead stick in the latter, and means within the magazine and operable incident to rotation of said tube to 95 effect movement of lead sticks in the magazine toward said aperture.

2. In a mechanical pencil, in combination, a hollow barrel portion, means for guiding 100 a lead stick therein, a sleeve mounted rotatably in said barrel portion and having a part forming a magazine wall, a magazine bottom having a central aperture, a lead guide tube having communication with the magazine through said aperture, and means operable 105 incident to rotation of said sleeve to effect movement of lead sticks in the magazine toward said aperture.

3. In a mechanical pencil, in combination, a lead guide tube, a sleeve rotatable relative 110 thereto, said sleeve having a portion forming the wall of a lead magazine above said lead guide tube, a magazine bottom affording an aperture for passage of lead sticks from said magazine into said lead guide tube, and a lead 115 positioning member extending inwardly of the magazine from the magazine wall for engagement with lead sticks in the magazine.

4. In a mechanical pencil, in combination, a hollow barrel portion, a lead guide tube 120 mounted therein, said lead guide tube being longitudinally slotted and flattened at one side, a traveler slidably longitudinally on the lead guide tube and fitting the flattened contour 125 thereof so as to be non-rotatable on said tube, 130

a lead-engaging member carried on the traveler in association with the flattened side of the tube, said lead-engaging member having a portion movable into and out of the bore 5 of the tube through said slot and adapted to travel longitudinally in the bore upon longitudinal movement of the traveler on the tube, and means for moving the traveler longitudinally on the tube to propel a lead stick 10 in the latter.

5. In a mechanical pencil, the combination as specified in claim 4 and including also a lug mounted on the traveler and adapted to travel in the slot of the lead guide tube ahead 15 of the lead-engaging member in the lead-propelling movement of the traveler.

6. In a mechanical pencil, in combination, a hollow barrel portion having a lead guide tube non-rotatably mounted therein, a sleeve 20 rotatably mounted in the barrel portion and encompassing the lead guide tube throughout the greater proportion of its length, said sleeve having a portion extending above the upper end of the lead guide tube and forming 25 the wall of a lead magazine, a bottom for the lead magazine having a central aperture for passage of lead sticks from the magazine into the lead guide tube, a traveler mounted to slide longitudinally but non-rotatably on 30 the lead guide tube, the lead guide tube being provided with a longitudinal slot, a lead-engaging member carried on the traveler and adapted to extend through said slot and into 35 engagement with the upper end of a lead stick in the lead guide tube, the sleeve being provided with a screw thread in its portion which encompasses the lead guide tube and the traveler having a portion meshing with 40 said thread whereby the traveler may be moved longitudinally for the greater proportion of the length of the lead guide tube by rotation of the sleeve.

7. In a mechanical pencil, in combination, a hollow barrel portion having a writing tip 45 at its lower end, a lead guide tube screw threaded to said tip and extending upwardly therefrom within the barrel portion, a sleeve rotatably mounted in the barrel portion in encompassing relationship to the lead guide 50 tube and having a portion extending above the upper end of the latter and forming the wall of a lead magazine, a bottom for said lead magazine mounted on the upper end of the lead guide tube and provided with an 55 opening for passage of a lead stick from the magazine into the lead guide tube, a traveler slidably longitudinally on the lead guide tube, a lead-engaging member on the traveler for engaging a lead stick in said tube, and 60 means operatively connecting the sleeve and traveler whereby rotation of the sleeve will propel the traveler longitudinally between the sleeve and lead guide tube.

8. In mechanical pencil construction, the 65 combination as specified in claim 7 and

wherein said rotatable sleeve has a portion extending beyond the upper end of the barrel, whereby it may be manipulated to rotate it within the barrel.

9. In a mechanical pencil, in combination, 70 a tip for holding a lead stick in writing position, a slotted lead guide tube non-rotatably secured to said tip and extending upwardly therefrom, a tubular member encompassing the lead guide tube throughout the greater 75 proportion of its length and extending above the upper end of the same to form the wall of a lead magazine, a bottom for the lead magazine carried on the upper end of the lead guide tube and provided with an aperture 80 whereby a lead stick may pass from the magazine into the lead guide tube, a traveler mounted to slide longitudinally on the lead guide tube, a lead-engaging member on the traveler adapted for engagement with a lead 85 stick in the lead guide tube, said tubular member being rotatable relative to the lead guide tube and tip, and means operatively connecting the traveler and tubular member whereby the former will be moved longitudinally 90 by rotation of the latter.

10. In a mechanical pencil, in combination, a tip for holding a lead stick in writing position, a slotted lead guide tube extending upwardly from said tip, a traveler slidably 95 longitudinally but non-rotatably on said lead guide tube, a plurality of lead-engaging members carried by the traveler in spaced relationship longitudinally thereof, said lead-engaging members adapted to travel in 100 slotted portions of the tube and to engage lead sticks positioned in the bore of said tube, a sleeve encompassing the traveler and lead guide tube and extending above the upper end of the latter to form the wall of a lead 105 magazine, said magazine having communication with the bore of the lead guide tube at the upper end of the latter, said sleeve being rotatable relative to the lead guide tube and traveler, and means operatively connecting 110 said sleeve and traveler whereby the latter may be moved longitudinally upon rotation of the sleeve.

11. In a mechanical pencil, in combination, a barrel having a lead-holding tip at its lower 115 end, a lead guide tube secured non-rotatably to the tip and extending within the barrel, a sleeve mounted rotatably within the barrel in encompassing relationship to the lead guide tube and having a portion extending 120 above the upper end thereof to form the wall of a lead magazine, a disk secured to the upper end of the lead guide tube and extending outwardly therefrom into association with the magazine wall, said disk being provided with an aperture for passage of a lead stick from the magazine into the lead guide tube, means operable by rotation of the sleeve for propelling a lead stick longitudinally in the lead guide tube, said sleeve being pro- 125

vided with means for cooperation with said disk to hold the sleeve against withdrawal from the barrel.

12. In a mechanical pencil, in combination 5 a rotatable sleeve having its lower portion screw threaded and its upper portion arranged to form the wall of a lead magazine, a slotted lead guide tube extending axially within said sleeve, a lead-holding tip secured 10 to the lower end of said lead guide tube, a disk secured to the upper end of said lead guide tube and forming the bottom of the lead magazine, said disk being provided with a central aperture permitting passage of a 15 lead stick from the magazine into the lead guide tube, a traveler slidable longitudinally on the lead guide tube from a position adjacent said disk to a position adjacent said tip, a lead-engaging member carried by the traveler and movable in the slot of the lead guide 20 tube to propel a lead stick therein, and means operatively connecting the traveler and sleeve whereby the former is propelled longitudinally upon rotation of the latter.
- 25 13. In a mechanical pencil, in combination, a hollow barrel portion, a lead-supporting tip abutting the lower end of said barrel, a lead guide tube screw threaded to the tip and extending axially within the barrel, a 30 member secured to and extending outwardly from the lead guide tube, a sleeve rotatably mounted in the barrel and encompassing the lead guide tube, said sleeve having an inwardly extending part adapted for cooperation with said member to retain said sleeve 35 against withdrawal from the barrel, the upper part of said sleeve forming the wall of a lead magazine having communication at its bottom with the upper end of the bore of 40 the lead guide tube, and lead feeding means cooperating with said sleeve and lead guide tube whereby a lead stick may be propelled longitudinally in the latter by rotation of said sleeve relative to the lead guide tube.
- 45 14. In a mechanical pencil, in combination, a hollow barrel portion, a lead guide tube mounted therein and extending axially thereof, said lead guide tube being longitudinally slotted at one side so that its width 50 is thereby reduced, a traveler embracing the lead guide tube and slidable longitudinally thereon and having a flatted portion engaging the grooved side thereof, whereby the traveler is held against rotation on the lead 55 guide tube, a lead-engaging member mounted on the traveler at the flatted side thereof and adapted to extend into the lead guide tube through the slot therein, a sleeve rotatably mounted in the barrel in encompassing 60 relationship to the traveler and lead guide tube, said sleeve and traveler having operative connection whereby the former may be moved longitudinally on the lead guide tube by rotation of the sleeve.
- 65 15. In a mechanical pencil, in combina-

tion, a lead-holding tip, a lead guide tube affixed thereto, a rotatable sleeve encompassing the lead guide tube and having its upper portion extending above the upper end thereof to form the wall of a lead magazine, 70 a bottom for said lead magazine affixed to the upper end of the lead guide tube and having an aperture permitting passage of lead sticks singly from the magazine into the lead guide tube, lead-feeding means operable by rotation of said sleeve relative to the lead guide tube to propel a lead stick in the latter, and means in the magazine and operable incident to rotation of said sleeve to move lead sticks 75 circuitously in the magazine.

16. In mechanical pencil construction, in combination, a hollow barrel portion having a tapered lower end, a sleeve arranged rotatably in the barrel, a lead guide tube arranged axially within the sleeve and having an outwardly projecting portion for cooperation with the sleeve to prevent its movement upwardly relative to the lead guide tube, a spacer encompassing the lead guide tube in position for abutment with the lower end of the sleeve, and a tip abutting the lower end of the barrel and having screw-thread engagement with the lead guide tube effective to retain the same and sleeve in 80 the barrel.

17. A mechanical pencil construction as specified in claim 16 and wherein said spacer is arranged for cooperation with the barrel and lead guide tube to prevent their relative rotation incident to the unscrewing of the 100 tip from the lead guide tube.

18. In a mechanical pencil, a lead-propelling element comprising a tubular sleeve having formed thereon a laterally projecting lug for meshing cooperation with a screw 105 thread, said sleeve having a flatted side and a lead-engaging element movable into the sleeve bore.

In testimony whereof I affix my signature.

JOHANN KOKSCHAROFF.
